CLAIM

The ornamental design for a display screen or portion thereof with graphical user interface, as shown and described.

DESCRIPTION

FIG. 1 is a front view of a first embodiment of a display screen or portion thereof with graphical user interface showing the new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof;

FIG. 9 is a front view of a ninth embodiment thereof;

FIG. 10 is a front view of a tenth embodiment thereof;

FIG. 11 is a front view of an eleventh embodiment thereof;

FIG. 12 is a front view of a twelfth embodiment thereof;

FIG. 13 is a front view of a thirteenth embodiment thereof;

FIG. 14 is a front view of a fourteenth embodiment thereof;

FIG. 15 is a front view of a fifteenth embodiment thereof; and,

FIG. 16 is a front view of a sixteenth embodiment thereof.

The broken lines shown in FIGS. 1-16 represent portions of the display screen or portion thereof with graphical user interface that forms no part of the claimed design.

1 Claim, 16 Drawing Sheets
